UNITED STATES PATENT OFFICE

RALPH W. STOCKWELL, OF WEBSTER GROVES, MISSOURI, ASSIGNOR TO LANGENBERG
MANUFACTURING CO., OF ST. LOUIS, MISSOURI, A CORPORATION OF MISSOURI

WARM-AIR FURNACE

Application filed January 20, 1928. Serial No. 248,037.

This invention relates to improvements in warm air furnaces, and consists in the novel construction hereinafter described.

An object of the invention is to provide a warm air furnace including a primary heating drum connected with a pair of heating drums having therein a tortuous gas passage resulting in an extended travel of the heated gases from the top of the primary heating drum through the pair of auxiliary drums, the gas leaving the furnace at a point near the bottom thereof, thereby providing an extended heat radiating surface.

Another object of the invention is to provide a construction of the type described in which the temperature in the area of the warm air outlet flues is substantially equalized.

Another object of the invention is to provide a construction of the type described in which heat radiating surfaces are substantially vertical and in which the free air areas are approximately equal in width, thereby obtaining a more perfect heat radiation, and also a reduction of stratification and eddy movements of the air coming in contact with the heating surfaces.

Another object of the invention is to provide in a type of construction above mentioned sufficiently large passes for the gas generated in the primary combustion chamber, particularly where the fuel is oil vapor or gas, to prevent an external explosion of the gas by accommodating the initial expansion thereof.

Additional objects of the construction will be apparent from the following detailed description taken in connection with the accompanying drawings, in which

Fig. 1 is a vertical section through the furnace substantially on the line 1—1 of Fig. 2.

Fig. 2 is a cross section through the furnace substantially on the line 2—2 of Fig. 1.

Fig. 3 is a broken rear elevation of parts of the furnace.

In the embodiment of the invention illustrated in the drawings, the invention comprises an outer shell 1 which is substantially oval in cross section and is designed to house the primary and secondary drums through

which the heated gas passes. This shell is mounted upon a base 2 and is provided with a cold air inlet 3 near the bottom thereof and a plurality of warm air outlet flues 4 arranged at spaced intervals around the circumference of the shell near the top. The shell is closed by a top wall 5.

In the forward part of the shell is the primary heating drum which comprises a cylindrical casing 6 divided into a combustion chamber 7 and a draft chamber 8, access to the combustion chamber being provided through a door 9 closing an opening through the shell, and access to the chamber 8 being obtained through a draft opening 10. The chambers 7 and 8 may be separated by grate bars or grate castings 11, and the lower portion of the chamber 7 may be lined with fire brick or other refractory lining 12.

It is to be understood that the construction is primarily designed for the use of oil or gas as a fuel, although it is not to be limited to vapor or liquid fuel as it is applicable also to the use of coal, coke, powdered fuel or the like, by providing suitable forced draft in accordance with well known practices.

Arranged in the rear of the primary heating drum is a pair of secondary drums each comprising an outer wall 13 and an inner wall 14, said two drums being arranged in parallel relationship and the walls being so spaced as to form oval rings with air passages 15 through the center thereof. Within each of the secondary drums are baffles 16 extending outwardly and baffles 17 extending inwardly in different horizontal planes from the baffles 16 thereby providing in the secondary drums a tortuous gas passage having a substantial cross area.

It will be noted that the secondary drums are spaced from the primary drum and also from the casing 1 so that the intervening spaces externally of said secondary drums and the internal spaces within the drums are of approximately the same area. It will be noted also that the side walls of the primary and secondary drums are substantially vertical, avoiding any irregularities so that passage of the air from the bottom of the shell 1 and in contact with the primary and sec-

ondary heating drums is in a vertical direction, which results in a high velocity of air movement over the entire heat radiating surface.

- 5 Each of the secondary drums is connected with the primary heating drum by a conduit 18 that leads from a point near the top of the primary drum into the upper portion of each of the secondary drums above the baffles 16. 10 The cross area of the tortuous passages in the secondary drums is large enough to provide for the initial expansion of the gas preventing external explosion and maintaining free 15 passage of the gas from the top to the bottom portion of said secondary drums. The lower passes of each of the secondary drums is connected with an outlet flue 19, which flues form a Y-connection with the stack 20.

Each of the secondary drums also may be 20 provided with spaced passages 21 that extend outwardly through the shell 1, the ends of which are closed by flap valves 22, thus providing means of access for cleaning the secondary drums and also as safety devices 25 that open outwardly in event of excessive pressure being generated in the secondary drums by an explosion of gas therein.

It will be noted that the secondary drums are supported on frames 23 at an elevation 30 above the base of the shell 1 to provide a cold air area at the bottom of the shell, which air passes upwardly in countercurrent to the heated gas within the secondary drums.

From the foregoing description it will be 35 observed that the construction affords a large heat radiating surface and a long gas travel, and that the hot gases enter at the top of the secondary drums and discharge at the bottom thereof. This downward movement of the 40 hot gases tends to prevent stratification thereof and also stratification of the air passing externally of the heating surfaces and prevents a back passage of the hot air into the air intake pipe. Since the cold air enters at the bottom of the secondary drums and passes 45 upwardly encountering the cooler portion of the secondary drums first, a countercurrent flow of the heating gases and the air being heated economizes in heat transfer and effects 50 a substantial saving of heat units.

Furthermore, the warmed air reaching the 55 top of the shell 1 is uniformly distributed in the area of the warm air outlet flues, thereby providing for an equal distribution of the warm air leader pipes connected into said flues.

Therefore, it is apparent that the construction greatly improves the efficiency of 60 warm air heating furnaces of the type mentioned, and fully accomplishes the objects hereinbefore set out. I am aware that the invention may be modified in numerous particulars without departing from the spirit 65 and scope thereof. I do not limit myself

unessentially, but what I claim and desire to secure by Letters Patent is:—

1. A warm air furnace comprising an outer vertical horizontally oblong wall enclosing a horizontally oblong space and having an air inlet opening near its lower end and warm air outlet openings near its upper end, a combined combustion chamber and heating drum enclosed by said wall near the wall thereof at one end of said space, two vertical O-shaped walls forming between them an O-shaped space and enclosed by said first wall between said primary heating drum and the opposite end of said first wall, a pipe opening from said primary heating drum into the upper end of said O-shaped space, a U-shaped wall closing said space below said pipe and leaving the opposite curved end of said O-shaped space vertically open, a second U-shaped wall below the plane of said first U-shaped wall closing the outer end of said U-shaped space and leaving open the inner end of said U-shaped space below said first U-shaped wall, and a pipe opening from the end of said O-shaped space below said second U-shaped wall.

2. A warm air furnace comprising an outer vertical horizontally oblong wall enclosing a horizontally oblong space and having an air inlet opening near its lower end and warm air outlet openings near its upper end, a combined combustion chamber and primary heating drum enclosed by said wall near one end of said space, two vertical horizontally oblong walls enclosed by said first wall and forming secondary heating drums between said combustion chamber and the opposite end of said space, an inner vertical oblong wall in and spaced from each of said walls of said secondary heating drums and forming air passages opening at their upper and lower ends into said space enclosed by said outer wall and forming vertical O-shaped spaces in said secondary heating drums, a pipe from said primary heating drum opening into the upper portion of each of said spaces, a horizontal U-shaped baffle wall in and closing each of said spaces below said pipe continuously for a distance along each side of said inner oblong wall 105 toward the outer end of said space and leaving vertically open the outer horizontally curved portion of said space, a second horizontal U-shaped baffle wall in and closing the outer portion of each of said spaces below said open space at the outer end of said first baffle wall and toward the wall of said secondary drum through which said pipe opens and leaving vertically open the inner horizontally curved portion of said space for the downward passage of products of combustion, and an outlet pipe opening from said outer secondary drum below said second baffle wall.

RALPH W. STOCKWELL.
